(57) **CLAIM**

The ornamental design for a collapsible crate, as shown and described.

DESCRIPTION

FIG. 1 is a perspective view of a collapsible crate showing my new design with the inserts removed from the crate for clarity of disclosure;

FIG. 2 is a front view thereof;

FIG. 3 is a back view thereof;

FIG. 4 is a top view thereof;

FIG. 5 is a bottom view thereof;

FIG. 6 is a left-side view thereof;

FIG. 7 is a right-side view thereof;

FIG. 8 is a perspective view of a collapsible crate with the inserts installed; and,

FIG. 9 is a top view thereof.

The dash-dot-dash lines shown on the bottom of the crate represent fold lines and the short broken lines on the surface of the crate represent stitching forming part of the claimed design.
